UNITED STATES PATENT OFFICE.

FRANK P. D'ARCY, OF KALAMAZOO, MICHIGAN.

CUSHION.

1,291,773.

Specification of Letters Patent. Patented Jan. 21, 1919.

Application filed July 13, 1918. Serial No. 244,786.

To all whom it may concern:

Be it known that I, FRANK P. D'ARCY, a citizen of the United States, residing at the city and county of Kalamazoo, State of Michigan, have invented certain new and useful Improvements in Cushions, of which the following is a specification.

This invention relates to improvements in cushions.

10 The main objects of this invention are: First, to provide an improved spring cushion structure.

Second, to provide an improved cushion structure in which the upholstering may be secured without sewing.

Third, to provide an improved cushion upholstering which is simple and economical to produce and strong and durable.

Fourth, to provide an improved cushion 20 in which the filler may be very conveniently and evenly arranged and is effectively retained as it is arranged within the upholstering without the aid of the usual tufting.

25 Further objects, and objects relating to structural details, will definitely appear from the detailed description to follow.

I accomplish the objects of my invention by the devices and means described in the 30 following specification. The invention is clearly defined and pointed out in the claims.

A structure which is a preferred embodiment of my invention is clearly illustrated 35 in the accompanying drawing, forming a part of this specification, in which:

Figure I is a front perspective view of a cushion embodying the features of my invention.

40 Fig. II is an enlarged detail vertical section illustrating one of the steps of manufacturing my improved cushion.

Fig. III is an enlarged detail vertical section showing another step of manufacture.

45 Fig. IV is an inverted view of the upholstering portion of my improved cushion with the skirt reversed or turned back.

Fig. V is a detail vertical section of a complete cushion.

50 Fig. VI is an enlarged detail section of certain parts shown in Fig. V.

Fig. VII is a detail section on a line corresponding to line 7—7 of Fig. VI.

Fig. VIII is a detail section on a line 55 corresponding to line 8—8 of Fig. III.

Fig. IX is an inverted perspective view of one of the fastening members or clips.

Fig. X is an inverted view of a modified form of the upholstered portion of my improved cushion.

Fig. XI is a detail transverse section of a complete cushion embodying the modifications shown in Fig. X.

Fig. XII is an enlarged detail section corresponding to that of Fig. XI.

Fig. XIII is a detail section on a line corresponding to line 13—13 of Fig. X.

Fig. XIV is a detail section similar to that of Fig. VIII illustrating one of the steps of manufacture of a modified embodiment of my invention illustrated.

Fig. XV is a detail vertical section corresponding to that of Fig. III, showing another embodiment of my invention.

Fig. XVI is a detail section on a line 75 corresponding to broken line 16—16 of Fig. XV.

Fig. XVII is a perspective view of a modified form of clip.

In the drawing similar reference characters refer to similar parts throughout the several views, and the sectional views are taken looking in the direction of the little arrows at the ends of the section lines.

Referring to the drawing, the springs 1 85 are of the helically coiled type and are mounted on a frame comprising top and bottom border wires 2 and 3, respectively, and the cross wires 4 and 5. As the details of the spring supporting frame form no 90 part of my present invention they are not further described herein.

The cushion upholstering comprises the top 6, back 7, and skirt 8, the top and back having a filling 9 between them. For convenience in illustration I have shown the top, back, skirt, and filler conventionally.

The top, back, and skirt are arranged with their edges superimposed or overlapping as shown in Fig. VI and if desired an 100 edging or beading strip 10 is disposed between the skirt and the top. The lapped or superimposed edges of the top, back, and skirt are, in the preferred embodiment, secured together by a plurality of metal fastening members or clips 11 cylindrically curved and formed of bendable metal, so that they may be clamped upon the overlapped edges securing them firmly without the necessity of sewing or other securing 110

means. These fasteners are provided with a plurality of alternately disposed teeth 12 on their edges, the teeth being embedded in the superimposed parts, the edge 13 between the teeth being in clamping engagement with the backing and facing or skirt. The fasteners may be very quickly and conveniently applied by means of a plier-like tool. When closed the teeth are embedded

10 in the material, as illustrated in Fig. VI.

The backing, designated generally by the numeral 7, is preferably formed of end sections 14 and central section 15 which overlaps the end of the end sections as shown 15 in Fig. VI. The object of this is that the backing may be secured along one side and its ends, as along edges *a* and *b*, *b*, in Fig. IV, and the sections folded back as indicated in Fig. II to permit the even spreading and 20 arranging of the filler 9 in the cushion.

In Figs. II and III I illustrate certain 25 steps in the manufacture of my improved cushion, the method and apparatus for carrying out the same, however, being substantially as shown and described in detail in my co-pending application.

Briefly, I provide a form 16 having a series of transverse flute-like channels 17 corresponding in dimensions to the roll-like 30 flutes 18 of the cushion. The top 6 is arranged on this form to fit into these channels 17 with the skirt 8 turned back over the form. The form is provided with kerfs 18 between the channels 17 adapted to receive the fluting fold supporting bars 19 with their edges projecting above the face of the form so that when the top is laid onto the form a series of fluting folds are formed 35 therein.

40 The filler box 20 is placed in position with its lower thin edge 21 fitting within the upwardly projecting thin edge 22 of the form holding the cushion top in proper position. The back sections are then turned back over 45 the filler box, the filler distributed and the press actuated. The press is provided with a plurality of follower bars 23 engaging the filling between the fluting folds 24 supported by the bars 19. The back sections are then 50 turned down over the filling. While held in this position clips 11' are engaged through the superimposed backing and top folds.

To facilitate engagement of the clips the bars 19 have notches 25 in their edges. 55 These notches also assist in the effective spacing of the clips as the top and backing will sag slightly at the notches indicating the proper position for the clips. After removing the filler box and the followers the 60 edge *c* of the backing is secured.

The upholstering thus formed has a series of convex flutings of uniform dimensions. The filler is confined in a series of compartments so that it is not likely to get out of 65 place. I find that cheap fillers, such as ex-

celsior, marsh grass, or other material, may be used, as it may be conveniently and evenly disposed, a layer of curled hair or other superior filler material having been first laid so as to secure a softer or more luxurious 70 effect, and at the same time keep the cost of manufacture low. The cushion is very attractive in appearance and is also very comfortable.

The securing of the overlapped edges of 75 the skirt top and backing together as by means of the clips provides a pocket or recess 26 at the edge of the upholstering top adapted, when the upholstering top is arranged upon the spring structure, to receive 80 the upper border wire 2 of the spring supporting frame. This serves as an effective anchoring means for the upholstering cover to the spring structure and prevents its working around thereon, which would tend 85 to wear the contacting parts, or the thin skirt coming into contact with the frame, which spoils the appearance. Further, the upper border frame is surrounded by filler. The skirt 8 is drawn over the spring supporting frame and secured to the upholstering 90 frame 27 as by means of the tacks 28, the upholstering frame illustrated being that shown in my application for Letters Patent, No. 81,485, filed March 1, 1916. 95

In the modification shown in Figs. X to XIV inclusive, the overlapped edges of the top, backing, and skirt are secured together by stitching 29, while the backing is secured to the top at 30 by means of stitching 31, 100 the steps of manufacture being substantially that described for the preferred construction with the exception that the backing 32 is a one-piece backing.

In the modification shown in Figs. XV, 105 XVI and XVII, the cover or top 6 has the flute-like form, with folds in the top embracing wires 33 retained by stitches 34. The top 6 is arranged in the form with these wires in place as shown in Fig. XV, the filling and packing being positioned and the 110 backing retained by clips 35 engaged over the backing and the wires. These clips 35 are not provided with teeth but securely bind the backing in place and also serve as 115 a retaining means for the top of the cushion, the clips being closed over the wire and its embracing fabric. The advantage of this construction is that there is no possibility of the fasteners being visible from the top of the cushion as sometimes might occur where the fasteners are provided with teeth and passed through the top as shown in Fig. III. This embodiment of my invention is very 120 satisfactory and strong and durable. The 125 embodiments shown in Figs. I to IX inclusive and XV to XVII are very satisfactory in that the cushion can be manufactured with great ease and rapidity and may be effectively manufactured by others than 130

skilled upholsterers and much more rapidly than other cushions with which I am acquainted and at the same time very high grade structures are produced.

5 Having thus described my invention, what I claim as new and desire to secure by Letters Patent, is:

1. In a cushion, the combination of springs and a spring supporting frame comprising top and bottom border members, an 10 upholstering top and back with a filling between, and a skirt, arranged with their edges superimposed and secured together by a plurality of bendable metal fasteners clamped around said superimposed edges of said top, back and skirt and having teeth on their edges embedded therein, the said superimposed edges and fasteners forming an inwardly facing pocket in which the upper 15 border member of the spring supporting frame is disposed, the lower edge of the skirt being connected to the bottom border member.

2. In a cushion, the combination of springs and a spring supporting frame comprising top and bottom border members, an 25 upholstering top and back with a filling between, and a skirt, arranged with their edges superimposed and secured together by a plurality of bendable metal fasteners clamped around their superimposed edges and engaging the under side of the top border member, the lower edge of the skirt being connected to the bottom border member.

3. In a cushion, the combination of springs and a spring supporting frame comprising a top border member, an upholstering top and back with a filling between, and a skirt arranged with their edges superimposed and secured together by a plurality of bendable metal fasteners clamped around the superimposed edges of said top, back, and skirt, said fasteners engaging with said top border member when the upholstering 40 is secured upon the springs and said skirt secured to the supporting frame.

4. In a cushion, the combination with a filling, of a top, back, and skirt arranged with their edges superimposed, bendable metal fasteners clamped around the superimposed edges of the top, back, and skirt, and having teeth embedded therein securing them together, said backing being formed of end sections and a central section overlapping said end sections so that said sections may be raised to permit the spreading of the filling after the said parts have been so secured at their ends and one side, said top having a plurality of fluting folds therein and said back having folds therein embracing the edges of said top folds, and bendable metal fasteners clamped around said back and top folds and having teeth embedded therein.

5. In a cushion, the combination with a

filling, of a top, back, and skirt arranged with their edges superimposed, bendable metal fasteners clamped around the superimposed edges of the top, back, and skirt and having teeth embedded therein securing 70 them together, said top having a plurality of fluting folds therein and said back having folds therein embracing the edges of said top folds, and bendable metal fasteners clamped around said back and top folds and 75 having teeth embedded therein.

6. In a cushion, the combination with a filling, of a top, back, and skirt arranged with their edges superimposed, bendable metal fasteners clamped around the superimposed edges of the top, back and skirt, securing them together, said backing being formed of overlapping sections so that said sections may be raised to permit the spreading of the filling after the said parts have 80 been so secured at their ends and one side, said top having a plurality of fluting folds therein, and bendable metal fasteners securing said back to the edges of the top folds.

7. In a cushion, the combination with a 85 filling, of a top having a plurality of fluting folds therein with bead wires laid in said folds, a back having folds therein embracing the fluting folds of said top with the wires laid therein, and bendable metal 95 fasteners clamped around the superimposed folds and wires therein.

8. In a cushion, the combination with a filling, of a top, back, and skirt arranged 100 with their edges superimposed and secured together, said backing being formed of overlapping sections so that said sections may be raised to permit the spreading of the filling after the said parts have been secured at their ends and one side, said top having a plurality of fluting folds therein to the edges of which the back may be secured after the filling has been placed and the sections folded down thereon.

9. In a cushion, the combination with a 110 filling, of a top having a plurality of fluting folds therein, a back having folds therein embracing the edges of the top folds, and bendable metal fasteners clamped about 115 the top and back folds and securing them together.

10. In a cushion, the combination with a filling, of a top having a plurality of fluting folds therein, and a back having folds therein embracing the edges of the top folds 120 and secured thereto providing a series of compartments for the filling, said back folds being secured upon the edges of the fluting folds.

11. In a cushion, the combination of a 125 top and back with filling between, and a skirt arranged with their edges superimposed, and a plurality of bendable metal fasteners clamped around the superimposed edges of said top, backing and skirt and se- 130

curing them together, said backing being formed of end sections and a central section overlapping said end sections so that said sections may be raised to permit the 5 spreading of the filling after the said parts have been so secured at their ends and one side.

12. A cushion comprising a top and back with filling between, and a skirt arranged 10 with their edges superimposed, a plurality of bendable metal fasteners clamped around the superimposed edges of said top, backing and skirt and securing them together, said backing being formed of overlapping sections so that said sections may be raised to 15 permit the spreading of the filling after the said parts have been so secured along three sides.

13. In a cushion, the combination with a 20 filling, of a top, back, and skirt arranged with their edges superimposed, and bendable metal fasteners clamped around the

superimposed edges of the top, back, and skirt, securing them together, said backing being formed of overlapping sections so 25 that said sections may be raised to permit the spreading of the filling after the said parts have been so secured at their ends and one side.

14. A cushion comprising a top and back 30 with filling between, and a skirt arranged with their edges superimposed and secured together, said backing being formed of overlapping sections so that said sections may be raised to permit the spreading of 35 the filling after the said parts have been partially so secured.

In witness whereof, I have hereunto set my hand and seal in the presence of two witnesses.

FRANK P. D'ARCY. [L. S.]
